UNITED STATES PATENT OFFICE.

EDWARD BOWEN, OF GILLETT, WISCONSIN.

TOOL FOR REMOVING VEHICLE WHEELS AND NUTS.

1,010,223.

Specification of Letters Patent. Patented Nov. 28, 1911.

Application filed May 23, 1911. Serial No. 629,088.

To all whom it may concern:

Be it known that I, EDWARD BOWEN, a citizen of the United States, residing at Gillett, in the county of Oconto and State 5 of Wisconsin, have invented certain new and useful Improvements in Tools for Removing Vehicle Wheels and Nuts, of which the following is a specification.

This invention has relation to tools for assisting the removal of vehicle wheels at 10 the time that the spindles are to be oiled, and has for its object to provide a simple mechanism which may be readily manipulated without the use of a jack for lifting 15 the wheel and its spindle so that the wheel may be readily slipped from the spindle upon a part of the tool, whereby the oiling of the spindle may be accomplished.

A further object of the invention is to 20 provide a pivoted socket member adapted to engage and remove a nut from the end of the spindle and hold the same during the time that the wheel is removed from the spindle.

25 For a full understanding of the invention reference is to be had to the following description and accompanying drawings, in which:

Figure 1 is a perspective view of the tool 30 applied to an axle spindle; Fig. 2 is a transverse sectional view of the tool; Fig. 3 is an end view of a member of the tool; Fig. 4 is a side view of the tool with a shaft adapted to be applied to a spindle located 35 at the left of the axle; Fig. 5 is a side elevation of the tool, parts in section, applied to an axle nut; Fig. 6 is a similar view applied to a spindle; Fig. 7 is a plan view of the tool; Fig. 8 is a perspective view of the 40 same.

Corresponding and like parts are referred to in the following description and indicated in all the views of the accompanying drawings by the same reference characters.

45 In case the tool is used upon the right hand spindles it is provided with right hand threads adapted to engage the threads of the spindles, and in case it is intended that the tool should be used at the left hand 50 spindles the shaft of the tool is provided with left hand threads for engaging the said spindles. With but this exception the tools used at the opposite sides of the vehicle are of the same pattern and design.

55 The tool consists of a shaft 1 which is provided at one end with a threaded socket

2 and at its other end with a handle 3. In that tool which is designed to be used upon the right hand spindles of the running gear the thread in the socket 2 is a right hand thread and in the tool designed to be used upon the left hand spindles of the running gear the thread in the socket 2 is a left hand thread. The tool which is designed to be used upon right hand spindles is 60 provided with a straight handle 3, while the tool designed to be used upon the left hand spindles is provided with an L-shaped handle 3, as illustrated in the drawing. This is to enable an operator to quickly 65 determine at which side of the running gear a specific tool is designed to be used.

A sleeve 4 is slidably mounted upon the shaft 1 and is provided at its outer end with a series of notches 5 which are adapted to partially receive the handle 3 when the parts are in the position shown in Fig. 1 of the drawing, so that the said sleeve 4 cannot rotate upon the shaft 1. The sleeve 4 is provided at its inner end with lugs 6 and an 70 upstanding shoulder 7. The member 8 is provided with a flange 9 which is pivoted between the lugs 6, and a spring clip 10 is mounted upon the member 8 and at times is adapted to frictionally engage the shoulder 7, whereby the member 8 is held approximately at a right angle to the sleeve 4. At other times the member 8 may assume longitudinal alinement with relation to the 75 sleeve 4. The member 8 is provided at its inner end with a circular socket 11 which at times is adapted to receive the inner end portion of the shaft 1, whereby the member 8 is held in longitudinal alinement with the 80 sleeve 4. The member 8 is provided at its inner end with a circular socket 11 which at times is adapted to receive the inner end portion of the shaft 1, whereby the member 8 is held in longitudinal alinement with the 85 sleeve 4. A cross bar 12 passes transversely through the member 8 and may be used as a handle to assist in turning the said member when the same is used for removing a nut from the end of a spindle. At its inner 90 end the member 8 is provided with a non-circular socket 13 which is adapted to receive the nut, indicated at 14, which is mounted upon the spindle 15 in the usual manner.

In operation when it is desired to remove a nut and wheel from a spindle, the socket 13 of the member 8 is placed over the nut 14, the said member 8 having previously been positioned in alinement with the sleeve 4 and the inner end of the shaft 1 received within the socket 11 of the said member. 100 By using the handles 3 and 12 the nut is 105 then unscrewed from the spindle, and when 110

it has become detached the member 8 is swung into an angular position with relation to the sleeve 4 and the clip 10 springs into frictional engagement with the shoulder 7 of the said sleeve. Thus the parts 4 and 8 are held at an angle with relation to each other, while the nut is still retained in the socket 13 of the member 8. The sleeve 4 is then slid back along the shaft 1 until its notches 5 engage the handle 3. The socket 2 is then screwed upon the end of the spindle, whereby the shaft 1 becomes fixed with relation to the spindle. Then by elevating the said shaft the wheel and spindle are elevated slightly so that the wheel clears the ground and may be readily slipped over the inner end portion of the shaft 1. The wheel being thus removed from the spindle ample room is provided for applying the axle 20 grease or oil to the spindle. After this has been done the operation above described is reversed, the wheel slipped back upon the spindle and the nut placed in position at the end of the spindle.

25 Therefore it will be seen that a simple and an effective tool is provided which may be readily manipulated for removing nuts and wheels from axle spindles and which in its operation does not require the use of a jack or other lifting devices.

Having thus described the invention, what is claimed as new is:

1. A tool for removing nuts and wheels from spindles comprising a shaft having at 35 one end a threaded socket adapted to engage the threaded end of a spindle, a sleeve slidably and rotatably mounted upon the shaft, and a member pivoted to the inner end of the sleeve and having at its inner end a socket adapted to at times receive the inner

end of the shaft, said member having at its other end a socket adapted to engage the spindle nut.

2. A tool for removing the nuts and wheels from spindles comprising a shaft 45 having at its inner end a threaded socket adapted to engage the threaded end of the spindle, said shaft being provided at its outer end with a transversely disposed handle, a sleeve slidably and rotatably mounted 50 upon the shaft and having at its outer end notches adapted to receive the handle of the shaft whereby the said sleeve is held against rotation with relation to the shaft, a member pivoted to the inner end of the 55 sleeve and having at its inner end a socket adapted to receive the inner end of the shaft, said member having at its other end a socket adapted to engage the nut upon the spindle.

3. A tool for removing nuts and wheels 60 from spindles comprising a shaft having at its inner end a threaded socket adapted to engage the thread at the end of the spindle, a sleeve slidably and rotatably mounted upon the shaft and having at its inner end a 65 shoulder, a member pivoted to the sleeve and having at its inner end a socket adapted to receive the inner end of the shaft, said member also carrying a clip adapted to have frictional engagement with the said shoulder when the member is swung at an angle to the sleeve, said member having at its other end a socket adapted to engage the nut of the spindle.

In testimony whereof, I affix my signature 75 in presence of two witnesses.

EDWARD BOWEN. [L.S.]
